UNITED STATES PATENT OFFICE.

CHARLES H. WARDWELL, OF RUTLAND, VERMONT, AND ROBERT D. MORRISON, OF PROVIDENCE, RHODE ISLAND.

CONTAINER FOR PASTE.

1,142,130.

Specification of Letters Patent. Patented June 8, 1915.

Application filed June 26, 1914. Serial No. 847,524.

To all whom it may concern:

Be it known that we, CHARLES H. WARDWELL, of Rutland, in the county of Rutland and State of Vermont, and ROBERT D. MORRISON, of Providence, in the county of Providence and State of Rhode Island, have invented a new and Improved Container for Paste, of which the following is a specification, reference being had to the accompanying drawings, forming part thereof.

This invention has reference to improvements in containers for semi-fluid paste adapted for use with brushes and particularly with dental brushes.

One object of the invention is to so construct a container of the nature herein described that the paste may be delivered automatically and progressively along the brush and that the flow of the paste may be readily cut off and the paste drawn backward from the outlet by suction.

Another object of the invention is to so construct a container of this nature that the brush may be guided in its movement relative to the delivery of the paste.

Another object of the invention is to so construct a container of this nature that a receptacle for the brush is provided.

Other objects of the invention will appear from the following description.

The invention consists in the container having the paste receptacle and the plunger having the outlet.

The invention also consists in such other novel features of construction and combination of parts as shall hereinafter be more fully described and pointed out in the claims.

Figure 1, represents a sectional view as taken on line 1—1 Fig. 2 illustrating the improved paste receptacle as constructed for use with an ordinary tooth brush. Fig. 2, represents a cross sectional view taken on line 2—2, Fig. 1. Fig. 3, represents a sectional view taken on line 1—1 Fig. 2 illustrating a modified construction of the device. Fig. 4, represents a view similar to Fig. 3 showing the brush receptacle telescoped into the paste receptacle.

Similar characters of reference designate corresponding parts throughout.

As shown in the drawings the paste receptacle 5 is cylindrical in shape and is closed at one end and open at the other end and has an internal screw thread. The

plunger 6 is also cylindrical in shape and has the exterior screw thread 7 adapted to be received by the screw thread of the paste receptacle 5. One end of this plunger 6 is closed by the member 8 having the orifice 9 which is in registry with the tubular paste delivery or mouth piece 10 and extending in lines parallel with said mouth piece 10 at the inner wall of plunger 6 are the guides 11, 11 between which the back A of a brush can be slidably received. The outer open end of the plunger 6 is cut away as at 12 to expose to view this end of said mouth piece 10 so that the delivery of paste from said mouth piece can be seen.

For use with a brush A having the rigid handle B we provide the closure 13 shaped to receive the handle B of the brush and having the enlargement 14 adapted to frictionally engage the exterior of plunger 6 and having the pocket 15 adapted to receive the outer end of the mouth piece 10. For use with the brush C which is adapted by reason of its size or construction to be wholly received by the plunger 6 we provide said plunger with the closure 16 hinged to the open end thereof and having the lip 17 which may engage exteriorly of said plunger 6 and having the pocket 18 adapted to receive the outer end of the mouth piece 10.

The paste receptacle 5 is filled nearly to its open end with paste P adapted to flow under pressure but not sufficiently fluid to escape between the screw threads of said receptacle 5 and plunger 6. Said plunger 6 is now screwed into receptacle 5 until its end 8 bears against the body of paste. The brush A or C, as the case may be, is usually in position in said plunger 6, which constitutes a brush receptacle, and if said brush be partially withdrawn and the plunger 6 be given a partial rotation to screw said plunger farther into the paste receptacle the end 8 of said plunger will compress the paste P and will force said paste to flow through orifice 9 and the tubular mouth piece 10 and such flow of paste will continue automatically under said pressure during a short period while the brush is being withdrawn so that during such withdrawal of the brush a comparatively small stream or core of paste is supplied thereto and is deposited along the center line of the bristles because of the fact that the brush is guided

in its movement by the guides 11, 11. When sufficient paste has thus been delivered to the brush the paste receptacle 5 and the plunger 6 are given a relative release rotation where-
5 by pressure of the plunger on the paste is relieved and the entrance of air, under atmospheric pressure, through the mouth-
piece 10 forces backward the paste in said mouthpiece. As the paste in receptacle 5 is
10 used the plunger 6 is received therein more and more thus continually shortening the combined exterior length of these parts when extended. By use of this device the paste may be used economically and when the recep-
15 tacle 5 becomes empty it may receive a new supply of paste.

Having thus described our invention we claim as new and desire to secure by Letters Patent.

20 1. A container comprising a brush receptacle having brush guiding members and a paste delivery mouth piece, which communicates with the exterior of said brush receptacle, and a paste receptacle adapted to

closely fit the exterior of said brush receptacle and to progressively receive said brush receptacle.

2. A paste container comprising a cylindrical paste receptacle having an inner screw thread, a hollow cylindrical brush receptacle having an end wall and an exterior thread adapted to engage with the screw thread of said paste receptacle, said brush receptacle having an orifice through its end wall, a mouth piece fixed to the wall of said brush receptacle and receiving from said orifice, and a closure for said brush receptacle.
